DESIGN FOR A CRUTCH

Thomas B. Brickson, Hollywood, Calif.

Application October 27, 1944, Serial No. 116,010

Term of patent 14 years

(Cl. D83—1)

To all whom it may concern:

Be it known that I, Thomas B. Brickson, a citizen of the United States, residing at Hollywood, in the county of Los Angeles and State of California, have invented a new, original, and ornamental Design for Crutches, of which the following is a specification, reference being made to the accompanying drawing, forming a part thereof, and in which

I claim:

The ornamental design for a crutch, substantially as shown.

THOMAS B. BRICKSON.
